UNITED STATES PATENT OFFICE

ALBERT W. BAILEY, OF NEW HAVEN, CONNECTICUT

SUPPORT FOR CHAIRS, STANDS, AND THE LIKE

Application filed March 28, 1927. Serial No. 178,901.

The present invention relates to means or devices for preventing the accidental toppling over of chairs, stands and the like; and the purpose of the invention is to provide automatic means of this kind, which are simple of construction and instantaneously operative when required.

According to the present invention, the improved means consists of one or more props or auxiliary legs capable of being applied to chairs, particularly high-chairs for infants; but the invention may be used with equal advantage with smoking stands, and numerous other articles of a similar nature, which stand on three or more legs and are apt to topple over.

In carrying out the invention, the improved means comprise as stated, one or more props or auxiliary legs, which are properly secured to the frame of the chair or stand. These legs are hinged so as to open outwardly and the opening of the legs is effected under action of a spring. These legs are each held in the closed position by a latch, which is automatically released when the chair, for example, is tilted into an angular position. When the chair is tilted the released auxiliary leg or prop is instantly thrown to its full open position, so that the chair is caught and held in a tilted position beyond the center of gravity.

It has previously been proposed to employ props or auxiliary supporting members swinging outwardly from chairs or stands for holding the same in an extreme tilted position, but heretofore such devices have been so arranged and constructed that they have to be set by hand into the operative position, or they are swung into that position by gravity; and in either instance the additional leg or prop is apt to be ineffective when the chair, for example, is suddenly tilted to an angular position beyond the center of gravity.

The invention will be hereinafter fully described, with reference to the accompanying drawing wherein:

Figure 1 is a side elevation of a high-chair, the same being shown by full lines in the perpendicular position, and by broken lines in a supported tilted position;

Figure 2 is a plan view showing the auxiliary legs or props in the open position; and

Figure 3 is a detail enlarged sectional view showing the auxiliary leg or prop with means for retaining it in its closed position.

Referring to said drawings, 1 represents a high-chair having the usual arm-rests 2, seat 3, foot-rest 4, and legs 5. 6 indicates the auxiliary legs or props, which preferably are provided at the back, front, and both sides of the chair. These legs 6 have feet 7 extended so as to provide a broader supporting base, and said legs 6 are hinged at 8 to the underside of the member of the chair constituting the seat. Preferably a spring hinge is employed, and in addition to this spring hinge, a leaf spring 9 may be employed so as to secure a quicker spring action to open the legs when this is required. Each leg 6 is braced by a folding member 10, which slides under a guide plate 11 secured to the leg 6. Each leg 6 has a pawl 13, which is engaged by a latching device 12 carried on a tripping member 14, the latter being pivotally connected to lug 15. The tripping member 14 is bifurcated so that the ends thereof will extend beyond the legs 5 of the chair at each corner.

In the operation of the improved device, when in the normal position, the legs are closed up against the sides of the article to which they are applied, and when the said article is tilted into an angular position beyond a determined point, the ends of the tripping device will be engaged with the floor so that said tripping device is forced upwardly, thus releasing the latch, and the auxiliary leg associated therewith. The prop so released will instantly fly outwardly and thus catch and support the chair, so as to prevent its toppling over. The tripping device is constructed and arranged so that should the chair, for example, be tilted in a diagonal angular position, two of the tripping devices

would be operated, thus a pair of the auxiliary legs would be thrown into operation so that the safety support for the chair would be effective along the line 16, as shown in Figure 2.

Certain modifications may be made in the

construction and application of the invention hereinbefore described and it is to be understood any modification coming fairly within the terms of the appended claims shall be covered thereby.

5 I claim:—

1. In combination with supporting means for chairs, stands or the like; an auxiliary spring operated leg or prop; means comprising a latch for retaining said leg or prop in its closed position; a tripping means for releasing said latch operating automatically and means comprising a spring normally under compression for throwing said leg or prop into its open or supporting position.
- 10 2. In combination with supporting means for a chair, stand or the like; a plurality of separately actuatable spring actuated auxiliary supporting legs or props located one at each side of said chair or stand; a latch for each leg or prop for retaining the latter in the closed position, an automatically operating tripping or releasing device for each latch and means comprising a spring normally under compression for throwing said legs or props into the open or supporting position.

Signed at New Haven, county of New Haven, State of Connecticut this 26th day of

30 March, 1927.

ALBERT W. BAILEY.
